UNITED STATES PATENT OFFICE.

GEORGE W. TUBBS, OF PHOENIX, NEW YORK.

STOVE-PIPE THIMBLE.

SPECIFICATION forming part of Letters Patent No. 279,205, dated June 12, 1883.

Application filed April 16, 1883. (No model.)

To all whom it may concern:

Be it known that I, GEORGE W. TUBBS, of Phoenix, in the county of Oswego, in the State of New York, have invented new and useful 5 Improvements in Stove-Pipe Thimbles, of which the following, taken in connection with the accompanying drawings, is a full, clear, and exact description.

This invention relates to that class of stove-pipe thimbles which are composed of telescopic sections adapted to be extended or contracted in length to conform to the thickness of the wall or ceiling through which they are to reach.

The invention consists in improved means 15 for adjustably retaining the thimble in its required length, as hereinafter fully described, and specifically set forth in the claims.

The invention is fully illustrated in the annexed drawings, wherein Figure I is a side 20 view of my improved stove-pipe thimble. Fig. II is a longitudinal section of the same. Fig. III is an end view, and Fig. IV a transverse section on line α α , Fig. II.

Similar letters of reference indicate corresponding parts.

A and A' are two cylinders adapted to slide 25 telescopically one over the other, and provided at their respective outer ends with a collar, B, by which the thimble embraces opposite 30 sides of the partition or ceiling through which the thimble extends. The outer cylinder, A, I form with a series of circumferential creases or grooves, a a , on the inside. The inner cylinder, A', I provide with spring-catches b , in 35 the form of spring-metal strips, fastened at one end to the interior of said cylinder, and having near their free end a short crimped or doubled portion, c , forming an outward-projecting lug, which protrudes through an aperture in the side of the cylinder A', and is 40 adapted to enter one of the grooves a of the outer cylinder, A, the extremity of said spring-plate extending over the end of the cylinder A' and part way into the joint between the 45 two cylinders, so as to retain said spring-plate in position.

The intermediate portion of the spring-plate has sufficient tension to hold the lug c engaged with the groove a with sufficient force to prevent the two cylinders from slipping telescopically by their own weight; but it has at the same time sufficient elasticity to allow the lug to spring out of the groove and automatically release the two cylinders when pressure is applied against opposite ends of the thimbles for contracting the same, or when manual force is exerted for drawing the two cylinders in opposite directions for extending the length of the thimble.

It will thus be observed that by the described construction and combination of parts I obtain a stove-pipe thimble which is simple in construction and very convenient and efficient in its operation.

Having described my invention, what I claim as new is—

1. The cylinder A, provided internally with circumferential grooves a a , in combination with the cylinder A', provided with the spring-catches b , substantially as and for the purpose 70 set forth.

2. In combination with the cylinder A, provided with the circumferential grooves a a , the cylinder A', sliding telescopically in the cylinder A, and the spring-plates b , fastened 75 at one end to the interior of the cylinder A', and having its free end extended over the end of the same and into the joint between the two cylinders, and formed intermediately of its length with the outward-projecting doubled 80 portion c , protruding through the side of the cylinder A', substantially as described and shown.

In testimony whereof I have hereunto signed my name and affixed my seal, in the presence 85 of two attesting witnesses, at Syracuse, in the county of Onondaga, in the State of New York, this 30th day of March, 1883.

GEORGE W. TUBBS. [L. S.]
